UNITED STATES PATENT OFFICE.

SEWALL Q. ROLLINS, OF BANGOR, MAINE.

MATTRESS.

Application filed September 11, 1924. Serial No. 737,076.

In mattress making various materials or combinations of material have been employed and variously embodied to produce that desired support of the body during the 5 hours of rest which constitutes so large and so important a part of life.

One of the materials of comparatively recent standard adoption is the kapok fibre or improperly so called "silk floss." This material, of ancient utility on its native soil has come to a general recognition and use in modern mattress making without having had general appreciation of its properties.

Specifically it has been found to be a mattress filler second only to the much more expensive hair fillings, but having some advantages over hair fillings.

Its problem factor is that of its advantage. It is a fibrous, silky, non-compacting material. It is hollow or cellular and in character apparently strongly adsorptive of air. Unfortunately it has its limits of endurance and cannot be successfully "stuffed" or hand packed in place. General practice has established blower methods as the best means of lodging the material in the place desired. Such methods are of necessity unequal in ultimate desired distribution. This has necessitated the beating out of mattresses to redistribute the material and particularly to build up corners and sides. Unfortunately such building up had to come from central expulsion. The general or average result was a depletion or overworking of the material at the centre of the mattress. This was partly understood or at least suspected, but it was not known how commercially to get distribution with anything like predetermined relation to center values.

The matter of such values is of greatest importance in view of the material which is involved as a characteristic factor in the present problem.

I have found that kapok, while of the most extraordinary fluffiness and of mass extension is considerably self dependent upon its internal mass relation. In other words, in isolated strands or small masses, it soon begins to disintegrate or "chowder" under wear.

It is a necessary prerequisite therefore to practical commercial usage that this kapok be used in sufficient local mass to allow it that self protection by which it may conserve itself under normal use.

It has been known that for ordinary mattress usage not less than 30 pounds should be

provided. It has been recognized that about 40 pounds was really needed for substantial wear.

The difficulty has apparently been in giving to the mattress that necessary localized mass by which its life at its vital centres might be sustained. The usual mattress failed at just the point of its maximum strain. A mattress whether used as single 65 or double, invariably shows maximum depression "usage" at about its center, i. e. the hip line of the incumbent or incumbents.

This unfortunately was just the spot of necessary attack in the beating out process. 70 This being true my present invention finds ample foundation in theory to explain the immediate practical successful results.

As illustrative of my method and as showing a characteristic article produced in accordance therewith I have shown in the accompanying drawing views intended to show practical theory though somewhat diagrammatical form.

Throughout specification and drawings 80 like reference characters are employed to illustrate corresponding parts.

In the drawings:

Fig. 1 is a diagrammatic view of the first step in this method of forming a mattress in 85 accordance with my invention.

Fig. 2 is a similar view of the second step.

Fig. 3 represents the third step.

Fig. 4 shows a cross section of a filled mattress, and 90

Fig. 5 a similar section of the finished mattress.

In practice I have made a shell or tick 1 of usual mattress form. In this is embodied a wall α preferably dividing the shell 1 into 95 chambers A, B and C.

The chambers B and C may be continuous but preferably are separable and are separated on the line $b-c$ in the course of my method.

The central drum or wall α provides the chamber A which I fill first preferably slightly above normal by weight as this region must still be the central distributing point of lateral pressures.

When this central chamber A is filled as shown in Fig. 1, the opening in its wall α is sewed up and the filling pipe S shifted to one side of the tick as shown in Fig. 2. At this point I close up the opposite end of the tick at the line $b-c$ by any temporary fastening so that the kapok is directed into the chamber B.

When this portion of the mattress has received its predetermined weight of filling, the filling pipe S is shifted in alignment with the chamber C into which a corresponding weight of material is blown. The ends of the tick are then sewed up.

The mattress now only requires a slight leveling. During such leveling the chamber A acts as an internal expansion member which transmits pressure to all parts of the mattress filling out the corners and sides without being itself sliced.

As a result I am able to produce mattresses having necessary mass of filling in each portion thereof and furthermore I am able to produce the mattress with a minimum of violence to the fibres in the center of the mattress.

At this stage, such a mattress would appear in cross section somewhat as illustrated in Fig. 4. The walls a of the central chamber are preferably slightly deeper than the outer shell of the mattress so as to permit the slight over-filling of chamber A. When the mattress is tufted and drawn down as in Fig. 5 it becomes substantially level. The central chamber A draws down substantially to the plane of the rest of the mattress.

While I have discussed my invention in connection with a mattress entirely filled with kapok it will be understood that other materials may be variously combined if desired. The different chambers might be filled with grades of kapok or of different materials and the steps might be varied in accordance with the materials used. The chamber A might be independently made and filled and might be otherwise initially expanded. I do not wish to be unreasonably limited to the particular fibre herein discussed. I do point out, however, that my invention is a very clear one in connection with such fibre as kapok and that such fibre is of great value if successfully used as in accordance with my invention. Furthermore my invention is not to be construed or limited to any particular weights or proportions, even mattresses of lighter weight, if proper distribution of the filling is maintained in predetermined relation, will be found to have greatly increased life.

In the case of hair or felt mattresses, the filling is not, of course, placed in the chambers by blower process, but the central chamber of any mattress constructed in accordance with my invention, has a relatively larger amount of filler than the outer shell. The amount may, of course, vary according to the nature of the filler, but regardless of the kind of filler, I believe any mattress made in accordance with my invention has longer life and affords more continued satisfaction than experienced with mattresses heretofore otherwise constructed.

What I therefore claim and desire to secure by Letters Patent is:—

1. The method of making a mattress consisting in vertically dividing the mattress tick to define a central chamber and a marginal surrounding chamber, in filling said central chamber with a relatively large amount of suitable mattress filling and sealing said chamber, in dividing said marginal surrounding area and filling first one half and then the other half thereof with a relatively less dense amount of mattress filling and closing each half of said divided surrounding chamber and levelling said central chamber and said surrounding chamber to form a mattress.

2. The method of making a mattress consisting in subdividing the tick container to produce a central chamber and leaving about said central chamber a marginal surrounding space, in first filling said central chamber with suitable mattress filling, sealing said chamber, in subdividing said marginal space, and first filling one-half of said marginal surrounding space and closing the same and then filling the other half and closing the same, and in levelling said chambers to form a mattress.

3. The method of making a mattress consisting in vertically dividing a mattress tick into a central compartment by means of a strip of ticking attached to the top and bottom of the mattress tick at predetermined points, in stuffing said central compartment and leaving thereabout a marginal surrounding space, in dividing said marginal surrounding space and stuffing said marginal space with a relatively less dense amount of filling than is contained in said central compartment, and in levelling the whole to form a mattress.

4. The method of making a mattress consisting in vertically dividing a mattress tick into a central compartment by means of a strip of ticking attached to the top and bottom of the mattress tick at predetermined points, in stuffing said central compartment and leaving thereabout a marginal surrounding space, and in stuffing said marginal surrounding space with a relatively less dense amount of filling, and in levelling the whole to form a mattress.

5. A mattress comprising a container having top, bottom and side walls, a vertically disposed inner wall composed of strips of ticking attached to the top and bottom walls of the container and defining a central chamber, a marginal surrounding chamber between the wall of said central chamber and the side walls of said mattress container, a relatively dense filling of suitable material in said central chamber and a relatively less dense filling in said marginal surrounding chamber, and tufting members drawing said densely filled central chamber to the level of said less densely filled marginal surrounding chamber.

6. A mattress comprising a container having top, bottom and side walls, a vertically disposed inner wall composed of strips of ticking attached to the top and bottom walls of the container and defining a central chamber, a marginal surrounding chamber between the wall of said central chamber and the side walls of said mattress container, a relatively dense filling of suitable material in said central chamber and a relatively less dense filling in said marginal surrounding chamber.
7. A mattress comprising a container having top, bottom and side walls, a vertical dividing wall between said top and bottom walls defining a central chamber, said dividing wall and side walls defining a marginal chamber surrounding said central chamber, a relative-
- ly dense filling within said central chamber, and a filling of other density than the density of said central chamber filling within said marginal chamber.
8. A mattress comprising a container having top, bottom and side walls, a member connecting said top and bottom walls and spaced inwardly from said side walls to define a central chamber, said member and said side walls defining a marginal chamber surrounding said central chamber, a relatively dense filling within said central chamber, and a filling of other density than the density of said central chamber filling within said marginal chamber.

In testimony whereof I affix my signature.
